A. L. TREESE.

COTTON PRESS.

APPLICATION FILED MAY 21, 1914.

1,125,768.

Patented Jan. 19, 1915.

UNITED STATES PATENT OFFICE.

ALBERT L. TREESÈ, OF CUSHING, OKLAHOMA, ASSIGNOR TO ANDERSON, CLAYTON & COMPANY, OF OKLAHOMA, OKLAHOMA, A PARTNERSHIP OR FIRM COMPOSED OF F. E. ANDERSON, W. L. CLAYTON, M. D. ANDERSON, AND BENJAMIN CLAYTON.

COTTON-PRESS.

1,125,768.

Specification of Letters Patent.

Patented Jan. 19, 1915.

Application filed May 21, 1914. Serial No. 840,019.

To all whom it may concern:

Be it known that I, ALBERT L. TREESÈ, citizen of the United States, residing at Cushing, in the county of Payne and State 5 of Oklahoma, have invented certain new and useful Improvements in Cotton-Presses, of which the following is a specification, reference being had therein to the accompanying drawing.

10 This invention relates to cotton presses of the type of which each has a plurality of rollers inclosing a cylindrical space in which a cylindrical bale is formed. In presses of this type it is necessary for some of the rollers to be movable to permit the bale to be 15 disengaged. These movable rollers are usually mounted on a movable frame section and this section must be very firmly secured in place when the baling operation is carried 20 on.

The object of my invention is to provide in a press of the type above referred to improved means for locking the movable frame section and the movable rollers in their normal 25 operative positions.

My improved features are well adapted for use in connection with a press such as that shown and described in my Patent No. 980,706, dated January 3, 1911, and in the 30 drawings, for purposes of illustration, I have shown a press similar to that shown in the said patent. I desire it to be understood, however, that my invention is not limited to the exact construction shown, but 35 may be used with other presses for which it is adapted.

Referring to the drawings, Figure 1 is an end view of a press embodying the invention, the view being partly in section along the line 1—1 of Fig. 2; Fig. 2 is a plan view 40 of the mechanism for controlling the opening and closing of the press, parts of the press being also shown in section along the line 2—2 of Fig. 1; Fig. 3 is a fragmentary 45 side view showing the lower parts of the press and the locking devices; Fig. 4 is a fragmentary sectional view showing one of the locking devices; Fig. 5 is a detail perspective view showing one of the elements of 50 one of the locking devices; Fig. 6 is a fragmentary view taken along the line 6—6 of Fig. 2.

Referring to the drawings, 1, 1 represent the main frame elements of the press. These

are positioned at the ends and are secured to 55 the base or foundation members 2, 2.

3, 3 are movable frame sections pivoted respectively to the main frame sections 1, 1 at 4.

5, 5 are horizontal rollers mounted in the 60 frame to inclose a substantially cylindrical space. Some of these rollers are carried by the fixed frame sections 1, 1 and others by the movable frame sections 3, 3. Each roller 5 carries a drive pinion 6, and all of the pinions 65 normally mesh with a central drive gear 7 which is connected to receive power by means of a belt wheel 8. The belt wheel 8 and the gear wheel 7 serve as driving mechanism for all of the rollers. It will be 70 seen that when the movable rollers are moved their pinions are disengaged from the gear 7, but will be immediately reengaged upon the return of the rollers to normal position.

75 For moving the movable sections 3, 3 of the frame each of them is connected to a rack 9. Preferably, these racks are rigidly connected to the respective sections and are curved to be concentric with the pivotal axes 80 of the sections at 4. 10, 10 are pinions mounted upon a longitudinal shaft 11 and engaging respectively with the said racks 9, 9. The shaft 11 carries a worm wheel 12 which meshes with a worm 13 on a transverse 85 shaft 14. Mounted on the shaft 14 are friction disks 15, 15 between which there is a cone friction driving pulley 16. The cone pulley 16 is mounted on a shaft 17, which is driven by means of the belt 18 and the belt 90 wheel 19. The shaft 17 is provided at 20 with a bearing in an eccentrically mounted sleeve. This sleeve carries an arm 21 which is connected to a hand lever 22 by means of a link 23. An operator, by moving the lever 95 22, can rock the sleeve through which the shaft 17 extends, and can in this way move the drive pulley 16 to the right or to the left to bring it into engagement with one or the other of the two friction disks 15, 15. It 100 will be obvious that when one disk is engaged the shaft 14 will be rotated in one direction, and that when the other disk is engaged the shaft will be rotated in the other direction.

105 The worm and worm wheel 13 and 12 serve as locking means for preventing the rotation of the shaft 11 by means of forces

applied to the pinions 10, 10. In this way the press is automatically locked closed against any small pressures tending to open it. But experience has demonstrated that 5 the pressure in a press of this type when cotton is being baled is so great that it is not safe to place final reliance upon the relatively small teeth of the pinion and the rack. In order to relieve these small teeth of the 10 pressure incident to the operation of the press I have provided adjacent each pinion a large supplemental tooth 23. Preferably, as shown in Fig. 5, this tooth is formed integrally with the pinion, and I find it advantageous 15 to construct it with an approximately spiral outline, as indicated. Connected to each of the frame sections 3, 3 is a depending lug 24 adapted to be engaged by the tooth 23 when the frame sections reach 20 their normal positions. These large heavy teeth 23, 23, by their engagement with the lugs 24, 24, take the strain tending, during operation of the press, to move the sections 3, 3. The strain is transmitted to the shaft 25 11 and from the shaft is transmitted to the worm wheel 13 which automatically locks the shaft against rotation, and hence automatically locks the press in closed position.

What I claim is:

- 30 1. The combination in a cotton baling press of a plurality of rollers arranged to normally inclose a cylinder, a roller carrying frame having a movable section by means of which some of the rollers can be moved out of their normal positions, driving mechanism for the rollers, means for moving the said movable section out of and into normal position, and a device supplemental to the moving means for locking the movable frame section in its normal operative position, the said device being connected to the moving means to be automatically moved into and out of operative position thereby.
- 35 2. The combination in a cotton baling press of a plurality of rollers arranged to normally inclose a cylinder, a roller carrying frame having a movable section by means of which some of the rollers can be moved out of their normal positions, driving mechanism for the rollers, a rack connected with the said movable section for moving it out of and into normal position, a rotatable driving pinion engaging the rack, a tooth rotatable with the pinion and supplemental to the teeth thereof, and a lug 40 connected with the movable frame section and positioned to be automatically engaged by the rotatable supplemental tooth when the movable frame section is in normal position.
- 45 3. The combination in a cotton baling press of a plurality of rollers arranged to normally inclose a cylinder, a roller carrying frame having a movable section by means of which some of the rollers can be moved out of their normal positions, driving mechanism for the rollers, a rack connected with the said movable section for moving it out of and into normal position, a rotatable driving pinion engaging the rack, a tooth rotatable with the pinion and supplemental to the teeth thereof, and a lug 50 connected with the movable frame section and positioned to be automatically engaged by the rotatable supplemental tooth when the movable frame section is in normal position.
- 55 4. The combination in a cotton baling press of a plurality of rollers arranged to normally inclose a cylinder, a roller carrying frame having a movable section by means of which some of the rollers can be moved out of their normal positions, driving mechanism for the rollers, two oppositely disposed similar racks connected with the said movable section for moving it out of and into normal position, two rotatable driving pinions engaging the racks respectively, two teeth rotatable respectively with the pinions and supplemental to the teeth thereof, and two lugs connected with the movable frame section and positioned to be automatically engaged respectively by the rotatable supplemental teeth when the movable frame section is in normal position.
- 60 5. The combination in a cotton baling press of a plurality of rollers arranged to normally inclose a cylinder, a roller carrying frame having a movable section by means of which some of the rollers can be moved out of their normal positions, driving mechanism for the rollers, a rack rigidly connected with the movable frame section, a rotatable driving pinion engaging the rack, a tooth rotatable with the pinion and supplemental to the teeth thereof, and a lug connected with the movable frame section and positioned to be automatically engaged by the rotatable supplemental tooth when the movable frame section is in normal position.

- 65 6. The combination in a cotton baling

press of a plurality of rollers arranged to normally inclose a cylinder, a roller carrying frame having a pivoted section by means of which some of the rollers can be moved out of their normal positions, driving mechanism for the rollers, a rack rigidly connected with the said pivoted section for moving it out of and into normal position, the rack being curved concentrically with the axis 70 of the pivot of the section, a rotatable driving pinion engaging the rack, a tooth rotatable with the pinion and supplemental to the teeth thereof, and a lug connected with the movable frame section and positioned to be automatically engaged by the rotatable supplemental tooth when the movable frame section is in normal position.

75 4. The combination in a cotton baling press of a plurality of rollers arranged to normally inclose a cylinder, a roller carrying frame having a movable section by means of which some of the rollers can be moved out of their normal positions, driving mechanism for the rollers, a rack connected with the said movable section for moving it out of and into normal position, a rotatable driving pinion engaging the rack, a tooth rotatable with the pinion and supplemental to the teeth thereof, a lug connected with the movable frame section and positioned to be automatically engaged by the rotatable supplemental tooth when the movable frame section is in normal position, and a worm and worm wheel for transmitting 80 power to the pinion and the supplemental tooth and for automatically locking them against retrograde movement.

85 5. The combination in a cotton baling press of a plurality of rollers arranged to normally inclose a cylinder, a roller carrying frame having a movable section by means of which some of the rollers can be moved out of their normal positions, driving mechanism for the rollers, two oppositely disposed similar racks connected with the said movable section for moving it out of and into normal position, two rotatable driving pinions engaging the racks respectively, two teeth rotatable respectively with the pinions and supplemental to the teeth thereof, and two lugs connected with the movable frame section and positioned to be automatically engaged respectively by the rotatable supplemental teeth when the movable frame section is in normal position.

90 In testimony whereof, I affix my signature, in presence of two witnesses.
